ROTARY SCREEN FOR SCREENING PULP AND PAPER STOCK

Filed Jan. 6, 1928

UNITED STATES PATENT OFFICE.

ERNEST W. LINDQUIST, OF HELSINGFORS, FINLAND.

ROTARY SCREEN FOR SCREENING PULP AND PAPER STOCK.

Application filed January 6, 1928. Serial No. 244,812.

This invention relates to rotary screens for screening pulp and paper stock and is more particularly directed to improvements in the machine forming the subject matter 5 of Patent No. 1,627,655 issued to me on May 10th, 1927. In that machine the apparatus embodies a plurality of screen sections arranged in annular series and interiorly of each of which is formed a chamber. The 10 inner wall of each chamber is in the form of a diaphragm which is adapted through manipulation of a cam to be flexed alternately in an inward and outward radial direction for the purpose of alternately sucking fine pulp through the screen sections and 15 thereafter discharging such pulp through a suitable outlet duct. In the said machine, the operations of the diaphragms were controlled by means of a cam positioned coaxially of the chambers and located in a more or less inaccessible position, so that it was 20 difficult to obtain access to the operating parts, and, moreover, the question of lubrication was somewhat of a problem since if 25 sufficient lubricant was introduced to properly lubricate the operation of the cam, this lubricant is apt to be distributed by centrifugal force throughout the whole interior part of the apparatus with attendant difficulties. Furthermore, the oily condition of 30 the parts resulting from this fact caused accumulation of dust and dirt which necessitated frequent cleaning.

The object of the present invention is to 35 overcome the disadvantage referred to and others by so positioning the cam and the followers or shoes which cooperate with it at the front end of the machine where they will be readily accessible for repair or adjustment and to enclose these operating parts in 40 such manner that they will not only be protected from dirt or dust but will run in oil, grease or other lubricant so that their operation will be substantially noiseless and efficient.

Another object of the present invention is 45 to provide for the operation of the diaphragms from a cam through interposed leverage connections so as to minimize the power required to operate the machine and to render such operation more smooth than heretofore.

Another object of the invention is to more 50 efficiently remove from the machine the screen product in order that the efficiency

and consequent protection of the machine may be increased.

A further object of this invention is to simplify the drive of the respective parts to eliminate excessive gearing with consequent 60 economy and elimination of noise.

Features of the invention, other than those specified, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a longitudinal section through apparatus embodying the present invention.

Figure 2 shows the apparatus of Figure 1 partly in end elevation and partly in transverse section.

Referring to the drawings, 1 designates a casing or vat which is of substantially cylindrical shape and is provided with an open top. This vat may be of wood or any other 80 suitable material and is supported in a suitable framework 2 mounted on an appropriate base 3.

Positioned within the vat 1 and mounted for rotation therein is a screen drum 4. This screen drum is positioned coaxially of the vat and is supported at one end by an axial trunnion 5 which is of hollow tubular section and is mounted to rotate in a bearing 6 supported by a standard 7 secured to the 90 base 3. The other end of the drum is in the form of an annular casting 8 which embodies a spider 9. This spider has a hub 10 mounted in a bearing 11 forming a part of a standard 12 which is also mounted on the 95 base. The drum 4 is provided with removable screen sections 14, each covering a segmental suction chamber 15 formed between longitudinal balks or partitions 16. The inner wall of the chamber 15 is in the form of a flexible diaphragm 17 which is secured to and extends between the partitions 29. Each screen section is provided with numerous fine slots as is customary.

The forward end of each of the suction 105 chambers 15 is closed by the casting 8, while the after end of each chamber communicates with the chamber 18 formed between the outer end wall 19 of the drum and an inner wall 20, so that fine pulp received within the 110

suction chambers 15 is adapted to readily exit with minimum resistance into the chamber 18 and thence through the passage 21 formed within the hollow trunnion 5. A shaft 22 is journalled at one end at the center of the inner wall 20 in a bearing 23 and extends forwardly through the apparatus and through the hollow trunnion or hub 10 of the spider 9 and is provided at its forward end with a pulley 24 by which this shaft may be driven. Fixed to the shaft 22 between the pulley 24 and the bearing 11 is a sprocket wheel 25 connected by a chain 26 to a sprocket wheel 27. This latter sprocket wheel is fixed to a shaft 28 which extends the full length of the apparatus and carries a sprocket wheel 29 at its opposite end. This latter sprocket wheel is connected by a sprocket chain to a sprocket wheel 30 fixed on the hollow trunnion 5 of the drum so that when the apparatus is driven by a belt cooperating with the pulley 24, both the shaft 22 and the drum will be driven.

It will be noted, however, that the driving connections are so constituted as to drive the shaft 22 at a greater speed than the drum 5. Fixed on the shaft 22 at the forward end of the machine and contiguous to the forward edge of the drum is a cam 31 adjacent the opposite faces of which are mounted plates 32 and 33. These plates have hubs which loosely embrace the shaft 22, so that the shaft 22 may rotate within the hubs of the plates 32 and 33 and at a greater speed than the speed of rotation of these plates. The plates are of disk form and are flanged at their outer peripheries and a cylindrical band or sleeve 34 of rubber or other suitable flexible material is demountably attached to these flanges so as to form with the plates 32 and 33 a closed cylindrical chamber in which the cam 31 is housed.

Positioned interiorly of the sleeve 34 are as many shoes as there are screen sections. These shoes 35 are juxtaposed with the respective sections and are adapted to act as followers with respect to the cam 31. Positioned exteriorly of the rubber sleeve and in juxtaposition with each shoe 35 is an attaching plate 36 which is secured to its corresponding shoe by means of screws extending through the plate 36 and through the rubber sleeve and threaded into the shoe so as to mount both the shoe and attaching the plate on the rubber sleeve. Each attaching plate has a ball joint connection 37 with the power arm of a lever 38. All of these levers extend longitudinally through the drum and are fulcrumed at 39 on the inner end wall 20, as shown in Figure 1. Intermediate the ends of each lever is pivoted a link 40 and this link is secured to a plate 41 attached to the diaphragm 17 of the corresponding suction chamber. The end frame or casting 8 is provided with outwardly ex-

tending lugs 43, one of which is juxtaposed with the free end of each lever 38 and a spring 42 is interposed between the end of each lever and the corresponding lug 43. These springs are of the compression type and serve to force the free ends of the levers in an inward radial direction for the purpose of maintaining the shoes 35 in engagement with the cam 31.

With this arrangement, the cam and its shoes are housed within a liquid tight casting which is adapted to be filled with lubricant through a suitable inlet 44 in order that these parts may run in grease in order to minimize friction and consequent wear and render the operation of the machine practically noiseless.

Mounted on the upper portion of the tank is an overflow box 45 into which the pulp to be screened is fed through an inlet 46 while the residue is fed out through a pipe 47. A spray pipe 48 is arranged to clean the screen sections as they rotate into the uppermost positions. The dirt, slivers and some stock flow over the edge of the tank into the overflow box and out through the outlet 47 in the usual manner. The lower portion of the tank is provided with a cleaning opening 49 adapted to be normally closed by the slide valve 50 which may be manually operated from time to time to clean out the tank.

The operation of the apparatus is as follows. Assuming that pulp is being introduced through the pipe 46 into the overflow box, this pulp will fill the tank exteriorly of the drum 14. If the apparatus is now started by rotating the pulley 24 through suitable driving connections, the drum will be rotated at a fairly slow speed while the cam will be operated at a somewhat higher speed by virtue of the connections described and both of these parts will rotate in the same direction. As the parts rotate, the cam traveling faster than the drum will act upon the shoes 35 to pivotally actuate the levers 38 and in so doing will alternately flex the diaphragms 17 of the suction chambers in opposite directions, thereby alternately subjecting the interior of the chambers to suction and pressure. At each suction operation, the finer pulp will be drawn through the slots in the screen sections into the chambers 15 and on each compression operation, the pulp which has thus been drawn in will be exhausted through the chamber 18 and through the passage 21 to a suitable draw off pipe for further treatment.

The operation is a continuous one and is found in practice to give highly efficient results. The interposition of levers between the cam following shoes and the diaphragms minimize the power required for the operation of the machine and the relatively simple driving connections which I have shown

greatly simplifies the operation of the device and minimizes its cost. There are no parts to get out of order and the fact that the cam and shoes operate within a bath of lubricant serves multi-fold purposes. In the first place, lubricant is thereby precluded from being deposited all over the interior of the drum as was heretofore the case, the parts work smoother and dust, dirt or extraneous matter is excluded from the working parts so that wear is minimized. The draw off of the screen material through the hollow trunnion 21 and through the relatively large chamber 18 increases the output of the machine since there is practically no back pressure or obstructions to the outlet of such screen material and there is no tendency therefore for the material drawn into the suction chambers to exit through the screen when the diaphragms are flexed in an outward radial direction.

I wish to call especial attention to the fact that the cam, its shoes and other operating connections at the work arm ends of the levers are positioned at the front end of the machine where they are of convenient access. It is not necessary with the machine of this invention, therefore, to reach into the interior of the drum to adjust, repair or replace any of these parts. A workman can stand exteriorly of the machine and all of these working parts are directly in front of him. This is of pronounced importance in the practical operation of machines of this character. The top of the tank is open, so as to allow ready access to the screen sections when desired.

The foregoing detailed description sets forth the invention in its preferred practical form, but the invention is to be understood as fully commensurate with the appended claims.

Having thus fully described the invention, what I claim as new and desire to secure by Letters Patent is:

1. In an apparatus of the character described, a screen drum circumferentially divided to form a series of circumferentially positioned suction chambers, each of which is provided with a diaphragm adapted to be flexed to produce suction in said chambers, a cam mounted coaxially of the drum, a plurality of shoes engaging with said cam, leverage connections between each shoe and one of the diaphragms, and means for producing relative rotation between the drum and the cam for the purpose of operating the diaphragm through the shoe and leverage connections.

2. In an apparatus of the character described, a rotary pulp screen divided into sections and each section forming the outer wall of a chamber, flexible diaphragms each closing a chamber corresponding to a screen section, and means for operating said dia-

phragms, said means comprising a cam mounted coaxially of the rotary pulp screen and at one end thereof, shoes cooperating with said cam, and leverage connections between the shoes and the respective diaphragms.

3. In an apparatus of the character described, a screen drum circumferentially divided to form a series of circumferentially positioned suction chambers, each of which is provided with a diaphragm adapted to be flexed to produce suction in said chambers, a cam mounted coaxially of the drum, a plurality of shoes engaging with said cam, leverage connections between each shoe and one of the diaphragms, and means for producing relative rotation between the drum and the cam for the purpose of operating the diaphragm through the shoe and leverage connections, and a closed casing enclosing and housing the shoes and the cam and adapted to contain a lubricant whereby the shoes and cam will operate within a lubricant bath.

4. In an apparatus of the character described, a rotary pulp screen cylinder provided interiorly with suction chambers, one wall of each of which embodies a diaphragm, a cam mounted to rotate coaxially of the cylinder, a plurality of shoes bearing on the cam, and each of which is operatively connected to one of the diaphragms, and a casing enclosing and housing all of the shoes and the cams and adapted to contain a lubricant whereby the shoes and cam will operate in a bath of lubricant.

5. In an apparatus of the character described, a rotary pulp screen cylinder provided interiorly with suction chambers, one wall of each of which embodies a diaphragm, a cam mounted to rotate coaxially of the cylinder, a plurality of shoes bearing on the cam, a lever secured to each shoe, and also secured to one of the diaphragms and each of said levers being fulcrumed to rotate with the cylinder, and springs for maintaining the shoes in engagement with the cam.

6. In an apparatus of the character described, a rotary pulp screen cylinder provided interiorly with suction chambers, one wall of each of which embodies a diaphragm, a cam mounted to rotate coaxially of the cylinder, a plurality of shoes bearing on the cam, a lever secured to each shoe, and also secured to one of the diaphragms and each of said levers being fulcrumed to rotate with the cylinder, springs for maintaining the shoes in engagement with the cam, and a liquid tight housing enclosing the shoes and the cam and adapted to contain a lubricant whereby the cam and shoes may operate in a lubricant bath.

7. In an apparatus of the character described, a screen drum embodying an annular series of suction chambers, the outer

- circumferential wall of each of which is perforated and the inner circumferential wall of each of which embodies a diaphragm, a cam positioned coaxially of and within the drum and adjacent one end thereof, a plurality of shoes bearing against the cam, a series of levers, one end of each of which is fulcrumed on the drum and which levers extend longitudinally of the drum and are secured at their opposite ends to the shoes, means for securing each lever to one of the diaphragms, and means for imparting rotary movement to the drum and cam with the cam moving at a higher speed than the cylinder, whereby the diaphragms are operated through the shoe and lever connections.
8. In an apparatus of the character described, a screen drum embodying an annular series of suction chambers, the outer circumferential wall of each of which is perforated and the inner circumferential wall of each of which embodies a diaphragm, a cam positioned coaxially of and within the drum and adjacent one end thereof, a plurality of shoes bearing against the cam, a series of levers, one end of each of which is fulcrumed on the drum and which levers extend longitudinally of the drum and are secured at their opposite ends to the shoes, means for securing each lever to one of the diaphragms, means for imparting rotary movement to the drum and cam with the cam moving at a higher speed than the cylinder, whereby the diaphragms are operated through the shoe and lever connections, and a liquid tight casing enclosing the cam and the shoes and adapted to contain lubricant, the wall of the liquid tight casing being flexible to permit operation of the shoes by the cam.
9. In an apparatus of the character described, a screen drum embodying an annular series of suction chambers, the outer circumferential wall of each of which is perforated and the inner circumferential wall of each of which embodies a diaphragm, a cam positioned coaxially of and within the drum and adjacent one end thereof, a plurality of shoes bearing against the cam, a series of levers, one end of each of which is fulcrumed on the drum and which levers extend longitudinally of the drum and are secured at their opposite ends to the shoes, means for securing each lever to one of the diaphragms, means for imparting rotary movement to the drum and cam with the cam moving at a higher speed than the cylinder, whereby the diaphragms are operated through the shoe and lever connections, and a liquid tight casing enclosing the cam and the shoes and adapted to contain lubricant, the wall of the liquid tight casing being flexible to permit operation of the shoes by the cam.

In testimony whereof I have signed the foregoing specification.

ERNEST W. LINDQUIST.
